PUMP

Robert S. Butler, Los Angeles, Calif., assignor to
 Nordberg Manufacturing Co., Milwaukee, Wis.,
 a Corporation of Wisconsin

Application March 17, 1932. Serial No. 599,487

16 Claims. (Cl. 103—148)

My invention relates to an improvement in pumps and has for one purpose the provision of a valveless pump. One exemplification of my invention is the provision of a valveless pump in which one or more flexible tubes are employed, the tubes having a wave-like movement imparted, for example, to one wall, whereby individual bodies of material being pumped are trapped between opposed walls of the tube or tubes and are moved longitudinally along the tubes in response to the wave-like movement of the approach and recession of the opposed sides of the tubes, the waves being true sine waves, travelling uni-directionally along the tubes. Another object is the provision of improved actuating means for a pump of the type herein described. Another object is the provision of means for preventing access of the material being pumped to the actuating mechanism. Another object is the provision of an improved flexible tube for use with such a pump. Other objects will appear from time to time in the course of the specification and claims.

I illustrate my invention more or less diagrammatically in the accompanying drawings, where-

25 in—

Figure 1 is a longitudinal section;

Figure 2 is a section on the line 2—2 of Figure 1;

Figure 3 is a section on the line 3—3 of Figure 1;

Figure 4 is a section on the line 4—4 of Figure 3;

Figure 5 is a section on the line 5—5 of Figure 3;

Figure 6 is a detail of one of the tubes employed;

Figure 7 is a section on the line 7—7 of Figure 6;

Figure 8 is an edge view of a securing member or wedge;

Figure 9 is a plan view of the member shown in Figure 8;

Figure 10 is a side view of one of the tubes, showing a variation;

Figure 11 is a section on the line 11—11 of Figure 10; and

Figure 12 is a similar section through another variation.

Like parts are indicated by like symbols throughout the specification and drawings.

Referring generally to the drawings, A indicates any suitable inlet passage for the material being pumped, and A¹ any suitable outlet or delivery passage. Secured to the passage A I illustrate the double passage member A² which may

be secured to the member A as for example by the bolts A³. It includes two branches or passages A⁴ A⁵ terminating for example in flanges A⁶.

Secured to said flanges A⁶ is a main pump structure or housing. Referring for example to Figure 2 which illustrates the main pump housing in section it may include a central or inner member B shown as having at one side the side or cover plate B¹ secured as by the screws B² and closed at top and bottom by partitions B³ B⁴ respectively having therein the lower bearing B⁵ and the upper bearing B⁶, the purpose for which will later appear.

Secured to each side of the central housing B is a side housing member including portions C, C¹ which may be secured together as by the bolts C² and may be secured to the housing B as by the bolts C³ penetrating flanges or lugs C⁴. Positioned within the outer or side housing so formed are the flexible tubes C⁵. As these tubes are identical except for a reversal of direction, only one will be described. Each such tube includes a side wall C⁶ abutting against the walls or inner faces of the members C C¹, as shown for example in Figure 2. Each such tube has at its upper and lower ends outwardly extending flanges C⁷ against which are positioned securing collars C⁸ which are engaged by locking wedges C⁹. The collars C⁸ have inclined faces C¹⁰ opposed to the corresponding inclined face of the opposed face of each wedge C⁹. The wedge C⁹ further engages shoulders C¹¹ formed respectively in the members C C¹ and in the opposed outer wall of the member B which extends outwardly as shown for example at C¹² C¹² in Figure 1. It will be understood that when the wedges C⁹ are driven home they strongly clamp the tube flanges C⁷ between the collars C⁸ and the opposed portions of the flanges A⁶ of the inlet passage A⁴ or against corresponding flanges A²⁰ of the outlet passages A²¹ as shown in Figure 1. Any suitable opening may be made in the members C or C¹ to permit the penetration of said wedges as shown for example at C¹⁴ in Figure 4. The wedges are illustrated as U-shaped and in order to fill the mouth of the U I provide a filling block C¹⁵ which may be held in position as by the screw C¹⁶. The wall C⁶ of the tube may be reinforced or stiffened as by the reinforcement C¹⁷ which extends into the flanges C⁷. The opposite or flexible wall of the tube has no such reinforcement but is exteriorly provided with a plurality of dove-tails C¹⁸ the purpose of which will later appear.

Rotatably mounted in the bearing sleeves B⁵ B⁶ is a shaft D which may carry at its lower end

110

a bevelled pinion D¹ in mesh with any suitable bevel gear D² mounted on a drive shaft D³. It will be understood that the shaft D³ may be rotated from any suitable power source not herein shown. The bottom B⁴ of the housing B is downwardly expanded as at D⁴ to give room for the shaft D³ and the gear D². The shaft D may be held in position as by a ball D⁵ resting in the seat D⁶ in the form of a screwthreaded plug. The ball D⁵ takes the vertical thrust of the shaft D and reduces friction. Any suitable bearings D⁷ D⁸ may be employed for the shaft D³, and I illustrate the bearing D⁷ as formed integrally with the bottom portion B³ of the housing B, while the bearing D⁸ is associated with the cover plate B¹. However, it will be understood that the driving connection and the mounting of the shafts may be made in a variety of manners.

Mounted for rotation with the shaft D are a plurality of eccentrics E. These eccentrics are helically arranged or distributed in relation to said shaft for a purpose which will later appear and are illustrated as of cylindrical exterior. Surrounding each said eccentric is a stirrup E¹ having flat bearing portions E² opposed to opposite sides of each said eccentric. The size of the stirrup is such that at all times the eccentric engages only the flat portions E² and preferably the fit is so close that there is no perceptible play between the eccentric and the opposed faces E². Extending in opposite directions from each such stirrup is a pin E³. The pins E³ pass through apertures E⁴ in the side walls of the chambers and penetrate into the space between said side walls and the flexible tubes above described. Each such pin carries at its end a cross piece E⁵ which may, for example, be screw-threaded thereto. Each such cross piece is in dove-tailed relationship with one of the dovetails C¹⁸ above described. E⁶ indicate packing members surrounding each pin E³ and herein shown as tapered to seat in corresponding tapered seats E⁷ formed in connection with the apertures E⁴. E⁸ are coil springs compressed between the packings E⁶ and the cross pieces E⁵. The springs tend to hold the packings firmly seated, thus maintaining a liquid proof closure about each pin E³. This is important in case of rupture of the flexible tube, since the fluid is thereby prevented from penetrating the central housing B which is preferably filled with oil to lubricate the various parts. In case of rupture the fluid which penetrates the space about the pins E³ may be drawn off through the passage E⁹ which may be open to the atmosphere. The purpose of the actuating connection above described is to effect the passage along each of the flexible tubes of a true sine wave having crests of approach and recession of the flexible wall from the rigid wall C⁶ of each tube. The eccentrics E are so formed and proportioned as to cause the travel of a true sine wave. In order to prevent wear and rupture of the flexible tube C⁵ at its ends or points of connection, I provide a lesser travel of the pins E³ nearest the top and bottom of the shaft D. This will be clear from the showing of the structure in Figure 1. The parts are so proportioned and the pins E³ of such length that the sine wave crests travel in staggered relationship uni-directionally along the two tubes. As shown in Figure 1 the crest of approach of one tube is opposite the crest of recession of the other.

Referring to the form of Figures 10 and 11, I illustrate a form of tube the fixed wall C⁶ of which is provided with a plurality of suction cups G

which perform the same function as the reinforcement C¹⁷ in preventing the normally fixed wall C⁶ from receding from the inner face of the members C C¹.

Referring to Figure 12 I illustrate a form of tube in which both sides are dove-tailed as at G¹, the dove-tailing being effective to secure the side C⁶ to the housing and to secure the opposite side to the cross-pieces E⁵.

It will be realized that whereas I have described and shown a practical and operative device, nevertheless many changes might be made in the size, shape, number and disposition of parts without departing from the spirit of my invention. I therefore wish my description and showing to be taken as in a broad sense illustrative and diagrammatic rather than as limiting me to my specific showing.

The use and operation of my invention are as follows:

Assume that two tubes are employed which communicate at one end through the passages A⁴ A⁵ with a common source of liquid and communicate at the other end through the passages A² A²¹ with a common outlet A¹. As to each individual stem or pair of stems E³, when it is in tube closing position in relation to one tube, it will be in tube expanding position in relation to the other, the movement of the two tubes being always opposite at any given point. The number of stems and eccentrics is such, in relation to the length of the device, that there is always a continuous closure in each tube. Referring for example to Figure 1 it will be understood that when there are two wave crests of closure in one tube, there will be at least one wave crest of closure in the other. There will never be less than one or more than two such crests of closure in the form of pump as herein shown. I do not wish to be understood to be limited to a maximum of tube, as under some circumstances I may wish to lengthen the device and provide a maximum of more than two. But it is essential that there should be a constant closure in each tube, as the closure point or crest performs the function of the valve of a pump, and without it the pump will not function. Referring to Figure 1, the trapped liquid X of the left hand tube exerts no pressure, and is merely trapped between wave crests. The zone of pressure or of effective application of force is always beyond the advance crest. In the opposite tube it is beyond the single crest illustrated. In the space between the two crests on the delivery side of the pump the liquid is under pressure, and directs back pressure against the walls of the tubes. This pressure is uniform, but its effective application is not. In the position of the parts shown in Figure 1 the effective application of pressure against the inclined wall shown at the left is not as great as the effective application of pressure against the horizontal wall shown at the right at the top of the tube. In one case it is directed against an inclined wall as at Y and in the other it is directed against a fully opened tube wall as Z. Therefore, the left hand is borrowing hydrostatic pressure from the right hand side, tending to assist in keeping the wave of crest closed. Note that the terminal fingers at each end of the pump have a travel somewhat less than that of the other fingers or cross pieces and do not come fully to closed position. This is necessary to prevent undue strain upon and breakage of the ends of the tubes.

Note also that the shaft D and its bearings and

the eccentrics E and the connections between the eccentrics and the members E² are all housed within the central closed housing B. In case of rupture of the tube the liquids will not penetrate the central housing. The only communication is about the stems and through the apertures E⁴. The packing means above described serve to maintain a liquid tight closure. Any suitable lubricant may be maintained within the housing B and a further advantage of the helical arrangement of the eccentrics rests in the fact that it may be employed to raise an oil or lubricant within the interior chamber. The lubricant will tend to ride up the central shaft and to flow down along the inside of the wall. An important advantage of the two tube type of pump herein shown, or of the employment of an even number of tubes, is the maintenance of hydrostatic balance, the delivery of an even flow of fluid.

It will be understood that although I have illustrated a two-tube type of pump that I may employ a single tube or a multiplicity of tubes.

I claim:

25. 1. In a pump, a pair of flexible walled chambers, and means for maintaining a uni-directional wave-like movement of approach and recession of opposed chamber walls simultaneously along both chambers, with the crests of the waves moving longitudinally along said chambers in staggered relationship.
25. 2. In a flexible tube pump, a tube member having a flexible wall, and means for producing a wave-like movement of said flexible wall, with crests of approach and recession, said means including a plurality of stems movable along axes perpendicular to the general longitudinal axis of said tube, said stems being connected to said wall.
40. 3. In a flexible tube pump, a tube member having a flexible wall, and means for producing a wave-like movement of said flexible wall, with crests of approach and recession, said means including a plurality of stems movable along axes perpendicular to the general longitudinal axis of said tube, said stems being connected to said wall, and actuating means for said stems, including a shaft and a plurality of eccentrics thereon in operative connection with said stems.
50. 4. In a flexible tube pump, a tube member having a flexible wall and means for producing a wave-like movement of said flexible wall, with crests of approach and recession, said means including a plurality of stems movable along axes perpendicular to the general longitudinal axis of said tube, said stems being connected to said wall, and actuating means for said stems, including a shaft and a plurality of eccentrics thereon, said eccentrics being helically arranged along said shaft, and being adapted to produce a true sine wave in the wall.
65. 5. In a pump, a chamber, a flexible wall, and means for imparting to said flexible wall a true sine wave movement having crests of recession and approach in relation to an opposed wall of said chamber, traveling uni-directionally along the wall.
70. 6. In a pump, a plurality of chambers, each having a flexible wall, and means for simultaneously imparting to the flexible wall of each of said chambers a true sine wave movement having crests of approach and recession moving uni-directionally along each said chamber, the crests in the two chambers moving in staggered relationship.

7. In combination with a pump having a flexible walled passage, a flexible wall for said passage, a driving shaft, a plurality of eccentrics helically arranged about said driving shaft, actuating stems in operative relationship with said eccentrics and adapted to be reciprocated thereby, means for constraining said stems to axial reciprocation, and an operative connection between each said stem and a flexible wall of said pump passage. 80

8. In combination with a pump having a plurality of passages, a flexible wall for each said passage, a driving shaft, a plurality of eccentrics, helically arranged about said driving shaft, actuating stems in operative relationship with said eccentrics and adapted to be reciprocated thereby, means for constraining said stems to axial reciprocation, and an operative connection between each end of each said stem and a flexible wall of one of said pump passages. 90

9. In a pump, a passage member, a flexible wall therefor, and means for imparting to said flexible wall a true sine wave movement having crests of approach and recession moving uni-directionally therealong, in relation to an opposed passage wall, an inner pump housing, and actuating means for imparting said sine wave, said actuating means being positioned within the inner pump housing, and liquid-tight closure means interposed between the actuating means and the flexible wall. 100

10. In a pump, a passage, a flexible wall therefor, an inner pump housing, pump actuating means within said inner housing, liquid-tight closure means interposed between the actuating means and the flexible wall, and actuating connections extending through said inner pump housing and closure means, said connections being secured, externally of said pump housing, to said flexible wall. 105

11. In a pump, a passage, a flexible wall therefor, an inner pump housing, pump actuating means within said inner housing, actuating stems extending through said inner pump housing, and liquid-tight packing means, about said stems, associated with said inner housing, the outer ends of said stems being in actuating connection with the flexible wall. 110

12. In a pump, a pump passage, a flexible wall therefor, and means for constraining said wall to a true sine wave movement having crests of approach and recession, said means including a shaft and means for rotating it, and connections between said shaft and the flexible wall adapted to move the flexible wall toward and away from an opposed wall in accordance with said true sine wave movement. 115

13. In a pump, a pump passage, a flexible wall therefor, and means for constraining said wall to a true sine wave movement having crests of approach and recession. 120

14. In a pump, a pump passage, a flexible wall therefor, and means for constraining said wall to a true sine wave movement having crests of approach and recession, said means including a plurality of driving members, and means for actuating them, and dovetail connections between said driving members and the flexible wall adapted to move the flexible wall toward and away from an opposed wall of the pump passage. 125

15. In a pump, a pump passage, a flexible wall therefor, and an opposed normally fixed wall, and means for imparting a wave-like movement to the flexible wall, with crests of approach and recession moving uni-directionally along said flex. 130

ible wall, said means including means for moving said flexible wall directly toward and away from the opposed normally fixed wall.

16. In a pump, a pump passage, a flexible wall therefor, and means for imparting a wave-like movement to said wall, having crests of approach and recession traveling uni-directionally thereon,

said means including a plurality of relatively rigid connecting and supporting elements associated with said flexible wall and adapted to resist pressure directed against the opposite face of said wall, and to impart full support to said wall.

ROBERT S. BUTLER.
